UNITED STATES PATENT OFFICE.

GEORGE KUKOVAC, OF CHICAGO, ILLINOIS.

COMBINATION CHARGE-FORMING APPARATUS.

Application filed April 26, 1928. Serial No. 272,990.

This invention relates to combination charge forming apparatus for internal combustion engines, and the primary object of the invention is to provide an apparatus of this kind through the use of which an internal combustion engine may be most efficiently operated to secure maximum power and economy of fuel.

A more specific object of the invention is to provide an apparatus of the above kind embodying a carbureter, and means for utilizing the heat within the crank case of the engine for heating and partially vaporizing the liquid fuel in its passage from the float chamber of the carbureter to the contact space of the latter where the fuel is mixed with air to form the explosive charge.

Still another object is to provide means for utilizing the heat of the lubricating oil in the engine crank case for heating the fuel and maintaining it in heated and partly vaporized condition when passing from the float chamber of the carbureter to the contact space of the latter.

A further object is to provide a charge forming apparatus characterized as specified above, and wherein means is provided for supplying oil vapors from the crank case of the engine to the contact space of the carbureter so as to form a part of the explosive charges supplied from the contact space of the carbureter to the engine cylinders.

Yet another object is to provide a charge forming apparatus of the above kind which is simple in construction and well adapted for ready installation upon conventional internal combustion engines.

Further objects will appear as the nature of the invention is better understood, and the same consists in the novel form, combination and arrangement of parts hereinafter more fully described, shown in the accompanying drawings and claimed.

In the drawings:—

Figure 1 is a fragmentary central vertical transverse section of an internal combustion engine equipped with a charge forming apparatus embodying the present invention; Figure 2 is a horizontal section taken on line 2—2 of Figure 1, to reveal details of construction of the carbureter; Figure 3 is a similar view taken on line 3—3 of Figure 1; Figure 4 is a still further similar view taken on line 4—4 of Figure 1; Figure 5 is a vertical section taken on line 5—5 of Figure 1, drawn on an enlarged

scale; Figure 6 is an enlarged horizontal section on line 6—6 of Figure 1; Figure 7 is an enlarged perspective view showing the lever for operatively connecting the float of the carbureter with the valve for controlling the flow of fuel into the float chamber; Figure 8 is an enlarged perspective view of the valve for controlling the flow of fuel into the float chamber; Figure 9 is a fragmentary view partly in elevation and partly in vertical section substantially on line 9—9 of Figure 1; Figure 10 is an enlarged fragmentary horizontal section taken on line 10—10 of Figure 1; Figure 11 is a top plan view of the unit forming part of the means for subjecting the fuel to the heat of the oil in the engine crank case and for supplying oil vapors from the engine crank case to the contact space of the carbureter; Figure 12 is an enlarged elevational view showing the clamping sleeve employed in installing the apparatus in connection with the crank case of the engine; Figure 13 is a transverse section on line 13—13 of Figure 12; Figure 14 is an elevational view of the slotted shell and strainer screen of the carbureter; Figure 15 is a central vertical section thereof; Figure 16 is an enlarged fragmentary side elevation of the air inlet pipe of the carbureter; Figure 17 is an end elevation of the seat for the fuel inlet float valve; and Figure 18 is a central longitudinal section of said valve seat.

Referring more in detail to the drawings, the present invention embodies a carbureter proper consisting of a float chamber or bowl 5 having an upper fuel inlet connection 6 at one side into which is threaded one end of an elbow 7 whose other end is adapted for connection with a fuel supply pipe, not shown. The connection 6 has an inwardly projecting extension provided with a bottom port adapted to register with similar ports in the elbow 7 and in a detachable valve seat 100 threaded in the inner end of the latter, as generally indicated at 8 in Figure 1. Depending from the inner end of the inner extension of the connection 6 is a vertical partition 9, and formed at the bottom of the adjacent side of the bowl 5 is a depression 10 into which the partition 9 partly projects to form a trap chamber 11 into which the fuel is supplied from the inlet connection 6. The partition 9 extends entirely across the trap chamber 11 so that the fuel must pass under the lower edge of the partition in entering

the main or float compartment 12 of the float chamber or bowl 5. In this way sediment is trapped in the chamber 11 and may be suitably drained therefrom through a bottom drain valve 13 provided on the depressed portion 10 forming the trap chamber 11. A lever 14 is pivoted as at 15 to a depending arm 14^a on the detachable seat 14^b of the elbow 7, and this lever 14 projects upwardly from its pivot and has a longitudinal undercut groove 16 in its outer side for removable sliding engagement with the head 17 provided on the inner end of a needle valve 18 which cooperates with the valve seat of the elbow 7 to control the flow of fuel into the bowl 5. A circular or ring-shaped float 19 is disposed within the bowl 5 and rigidly carried at one side by the lower end of the lever 14. By reason of this construction the float 19 is adapted to close the valve 18 when the fuel reaches a predetermined level with the chamber 12 of the bowl 5, and to open the valve 18 when the level of the fuel within the chamber 12 is lowered below said predetermined level. The action of this construction is generally well known in the art, it being evident that a substantially constant predetermined level of fuel is maintained in the float chamber in this way, automatically. The float 19 preferably has a channel in its underside as at 20 to form an air trap and enhance the buoyancy of the float whereby the float valve mechanism is rendered extremely sensitive in action. Moreover, the undercut groove 16 in the lever 14 preferably opens through the top end of the latter to facilitate assembly of the valve 18 with relation thereto. The bowl 5 has an open upper end closed by a cover plate 21 which is formed with a central depending hollow portion 22 enclosing a contact space 23 and formed with an integral depending cylindrical stud 24 on the bottom thereof projecting through and snugly fitted in a central opening provided in the bottom of the bowl 5. A nut 25 is threaded upon the projecting lower end of the stud 24 against the bottom of the bowl 5 so that the cover plate 21 is tightly drawn in place upon the top of the bowl 5. Any suitable sealing means is provided between the bowl 5 and the cover plate 21 and between the nut 25 and the bottom of the bowl 5 for effecting a water-tight joint. The hollow portion 22 depending from the cover plate 21 has a lateral tubular extension forming an inlet 26 through which air is admitted into the contact space 23 for forming part of the explosive charges. This air inlet preferably extends upwardly through the cover plate 21 and laterally therefrom above the top of the bowl 5 as shown clearly in Figure 5.

A further hollow part 27 is formed on top of the cover plate 21, and this hollow part 27 has an upstanding pipe 28 adapted as at

28^a to be coupled at its upper end with the intake manifold of the engine 29 for supplying the explosive charges to the cylinders of said engine in any well known or preferred manner. The cover plate 21 has a suitable port to provide communication between the contact space 23 and the outlet pipe 28, and this port is controlled by a suction operated valve 29 which is preferably hinged to swing upwardly to open position, and which is adapted to automatically lower to closed position under the action of gravity. Suitable means is provided as at 30 to adjustably limit the opening swinging movement of the valve 29 so that it may open the required degree and yet limited in opening movement so that it will promptly close when suction ceases in the outlet pipe 28. Such as suction operated valve has well known further functions and needs no more detailed discussion. 35

A conventional butterfly valve 31 is provided in the outlet pipe 28 for controlling the volume of charge admitted to the engine cylinder, and provided in the outlet pipe 28 above this valve 31 is a suitable mixing device to insure thorough mixing of the constituent parts of the explosive charges immediately prior to supply thereof to the engine cylinders. As shown, the upper end of the outlet pipe 28 is formed with a spherical enlargement 32 which is slotted at one side and provided with outwardly projecting flanges 33 at the top and bottom of this slot. A horizontal arm 34 has its outer end fitted in the slot and between the flanges 33, being rigidly secured to the latter by a bolt 35. In this way, the arm 34 is rigidly fastened in place to project inwardly to the center of the spherical portion 32. Journaled as at 36 upon the top and bottom of the inner end of the arm 34 are horizontal screw impellers 37 and 38 respectively having their blades twisted in opposite directions so that when suction occurs in the pipe 28, these impellers are caused to rotate oppositely for most effectively breaking up the fuel and intimately mixing the constituent parts of the explosive charges. 110

The stud 24 has a longitudinal passage 39 near the side adjacent the trap chamber 11, and the upper end of this passage opens laterally through the adjacent side of the stud 24 into the bottom of the float chamber 12 of the bowl 5, the passage 39 opening at its lower end through the bottom of the stud 24, as shown. Disposed about the portion of the stud 24 within the bowl 5 and interposed between the bottom of the latter and the bottom of the hollow portion 22 is a rigid perforated or slotted shell 40 which is disposed in spaced concentric relation to the stud 24 and securely clamped between the bottom of the hollow portion 22 and the bottom of the bowl 5 when the nut 25 is tightened. A cylindrical strainer screen 41 of fine wire mesh 125

snugly fits above the sleeve 40, and in this way the liquid fuel is allowed to pass from the chamber 12 of the bowl 5 into the passage 39 at numerous points entirely about the stud 24. In other words, the fuel may find its way within the sleeve 40 at numerous points entirely about the stud 24 so as to ultimately and readily find its way to the passage 39 even though different portions of the strainer screen 41 may become plugged with sediment which it is adapted to catch. This insures proper straining of the fuel should sediment not be entirely trapped in the chamber 11 or should the latter be allowed to accumulate an excessive amount of sediment or foreign matter.

A further passage 42 extends longitudinally of and entirely through the stud 24 so as to open at its upper end into the contact space 23 and at its lower end through the bottom of the stud 24 as shown in Figure 1. A suitable valve seat is provided in the upper part of the passage 42 for engagement by a manually adjustable needle valve 43 which extends upwardly through a stuffing box 44 on top of the hollow part 27 of the cover plate 21 and has a suitable handle or finger piece 45 outside of and above the portion 27 for convenient manipulation and adjustment of the valve 43. This valve 43 is adapted to regulate the volume of fuel supplied to the contact space 23 as will later become apparent.

The invention further embodies a relatively long return bent tube 46, the legs of which are curved and in adjacent relation, and the intermediate portion of which is formed or bent to provide a heating coil 47 disposed within the crank case 48 of the engine 29 below the level of the lubricating oil in the crank case. One end of the tube 46 is connected with the lower end of the passage 39, while the other end of the tube 46 is connected with the lower end of the passage 42, and it is thus apparent that the liquid fuel supplied from the chamber 12 of the carburetor bowl 5 will be conducted through the tube 46 from the passage 39 to the passage 42 and then into the contact space 23, the fuel being heated and partly vaporized in passing through the coil 47 which is submerged in the heated lubricating oil in the crank case 48. The major portion of the tube 46 extends longitudinally of and within a curved pipe 49, one end of which enters the bottom of the crank case 48 and terminates in upwardly projecting inlet branches 50 whose upper inlet ends are suitably shielded as at 51 to prevent oil from entering the same when it is splashed about in the crank case through the operation of the cranks of the crank shaft 52 and the connected ends of the pitmen which operatively connect the cranks of the crank shaft 52 with the pistons of the engine 29 working in the power cylinders of the latter. These branch inlets 50 extend above the level of the lubricating oil in the crank case and oil vapors generated in the crank case are adapted to be conducted from the upper portion of the crank case through the pipe 49 into a further longitudinal passage 53 provided entirely through the stud 24. The other end of the pipe 49 is therefore reduced and connected to the lower end of the passage 53, and the latter passage is provided at its upper end with a lateral outlet 54 which opens into the contact space 53. The oil vapors from the crank case are thus conducted to the contact space 23 for being mixed with the fuel and air admitted to the latter, and forming a constituent part of the explosive charges supplied to the engine cylinders. A suitable needle valve 55 is disposed adjacent the needle valve 43 and associated with a seat 56 at the upper end of the passage 53 for regulating the flow of vapors from the latter into the contact space 23, it being understood that these vapors are drawn into the contact space by suction in the same well known manner that the fuel and air are drawn into said contact space, when the engine is placed into operation. A tubular jacket 56 encases the pipe 49 and tube 46 except the coil portion 47 and inlet branches 50, and one end of this jacket is suitably coupled as at 57 to the projecting lower end of the stud 24 to provide a fluid tight joint, while the other end of the jacket is fastened to the bottom of the crank case 48 as at 58 to provide a fluid tight connection and form communications between the interior of the crank case and the interior of the jacket 56. In practice, the carburetor proper is suitably mounted beside the engine 29 above the level of the lubricating oil in the crank case, and this lubricating oil is adapted to enter and fill the jacket 56 so as to utilize the warmth of the lubricating oil in said jacket 56 for maintaining the fuel and vapors passing through the tube 46 and the pipe 49 in heated and vaporized condition. As shown, the end of the jacket 56 which is connected to the crank case 48 has a split sleeve 59 fastened therein, and this sleeve projects upwardly into the crank case where it is clamped as at 60 securely about the adjacent end of the pipe 49 to rigidly fix it against vibration to an excessive degree. The clamping sleeve 59 is provided with a plurality of slots 61 to afford passage for the lubricating oil from the crank case 48 into the jacket 56.

As indicated in Fig. 1 and clearly shown in Figure 9, the jacket 56, pipe 49; and tube 46 are located with respect to the crank case 48 so that the coil 47 is disposed directly beneath the partition 62 which carries the main center crank shaft bearing 63 of the engine, while the branch inlets 50 project upwardly at opposite sides of the partition 130

62 between the latter and the adjacent cranks 64 of the crank shaft. By this arrangement, a most desirable instillation is had without interfering with the operation of the crank 5 64 and so that the vapors are effectively derived from the top of the crank case at both sides of the partition 62 at a zone where the greatest heat is encountered. This benefit is also derived by the similar location of the 10 coil 47.

In operation, the fuel is drawn from the chamber 12 through the tube 46 into the contact space 23, thereby passing through the coil 47 and being partly vaporized and 15 heated. The operation of the engine causes suction in the contact space 23 for effecting this action in a well known manner, and this suction simultaneously causes vapors to be withdrawn from the top of the crank case 20 through the pipe 49 into the contact space 23, along with fresh air which enters the air inlet 26. The air, oil vapors and heated and 25 vaporized fuel are delivered together in proper proportions within the contact space 23, thereby forming explosive charges which are conducted to the engine cylinders from the outlet pipe 28. Due to the nature of the 30 constituent parts of the explosive charges and the condition in which they are combined, a most thorough mixing of said constituent parts is insured after final mixing 35 operation effected by the impellers 37 and 38. Moreover, the heating and partial vaporization of the fuel and the additional supply of 40 crank case vapors insures economical and efficient operation of the engine, the explosive charges being in a condition for instantaneous ignition when admitted in the engine cylinders. The construction is extremely simple and furnishes such protective 45 nature as to insure continued faultless operation under ordinary conditions of use, while ample provision is made for facilitating assembly or separation of parts for renewal, repair or cleaning.

A valve 70 is provided to control the volume of air admitted through the inlet pipe 26, a lever 71 being provided to permit manual closing of said valve, and a spring 72 50 being associated with the lever 71 to normally yieldingly turn the valve to open position. Stop means 73 limits swinging of lever 71 to a position wherein the valve 70 is fully open.

55 While I have shown and described a preferred embodiment of the invention which has given satisfactory results in service, it is nevertheless to be understood that minor changes may be made without departing 60 from the spirit and scope of the invention as claimed.

What I claim as new is:—

1. The combination with a carbureter having a contact space provided with air and 65 fuel inlets; a float chamber provided with a

fuel inlet and a fuel outlet, and the crank case of an internal combustion engine, of a tube to conduct the fuel from said fuel outlet of the float chamber to said fuel inlet of the contact space and having a portion 70 forming a heating coil adapted to be submerged in the body of lubricating oil in the crank case of the internal combustion engine, and means including a pipe encasing the major portion of said tube for conducting 75 oil vapors from the engine crank case to said contact space.

2. The combination with a carbureter having a contact space provided with air and fuel inlets, a float chamber provided with 80 a fuel inlet and a fuel outlet, and the crank case of an internal combustion engine, of a tube to conduct the fuel from said fuel outlet of the float chamber to said fuel inlet of the contact space and having a portion 85 forming a heating coil adapted to be submerged in the body of lubricating oil in the crank case of the internal combustion engine, means including a pipe encasing the major portion of said tube for conducting oil 90 vapors from the engine crank case to said contact space, and a tubular jacket surrounding said tube and said pipe and adapted for connection with the crank case to derive and be filled with oil from the latter. 95

3. In a charge forming apparatus for internal combustion engines, a carbureter proper having a contact space provided with air and fuel inlets, a float chamber provided with a fuel inlet and a fuel outlet, and the 100 crank case of an internal combustion engine, a member having passages forming said fuel outlet of the float chamber and said fuel inlet of the contact space, a tubular jacket coupled at one end to said member and 105 adapted for communicating connection at its other end with the crank case of the internal combustion engine to be filled with lubricating oil from the latter, and a tube extending through said jacket for conducting the fuel from the fuel outlet of the float chamber to the fuel inlet of the contact space. 110

4. In a charge forming apparatus for internal combustion engines, a carbureter 115 proper having a contact space provided with air and fuel inlets, a float chamber provided with a fuel inlet and a fuel outlet, and the crank case of an internal combustion engine, a member having passages forming said fuel 120 outlet of the float chamber and said fuel inlet of the contact space, a tubular jacket coupled at one end to said member and adapted for communicating connection at its other end with the crank case of the 125 internal combustion engine to be filled with lubricating oil from the latter, and a tube extending through said jacket for conducting the fuel from the fuel outlet of the float chamber to the fuel inlet of the contact 130

space, said tube having an intermediate portion disposed outside of and adjacent said other end of the jacket and forming a heating coil adapted to be submerged in the body 5 of lubricating oil within the engine crank case.

3. In a charge forming apparatus for internal combustion engines, a carbureter proper having a contact space provided with air and fuel inlets, a float chamber provided with a fuel inlet and a fuel outlet, and the crank case of an internal combustion engine, a member having passages forming said fuel outlet of the float chamber and said fuel 10 inlet of the contact space, a tubular jacket coupled at one end to said member and adapted for communicating connection at its other end with the crank case of the internal combustion engine to be filled with lubricating oil from the latter, a tube extending through said jacket for conducting the fuel from the fuel outlet of the float chamber to the fuel inlet of the contact space, said tube having an intermediate portion disposed outside of and adjacent said other end of the jacket and forming a heating coil adapted to be submerged in the body 15 of lubricating oil within the engine crank case, said member having a still further passage forming a vapor inlet for the contact space, and a pipe extending through said jacket for conducting oil vapors from the crank case of the engine to said vapor inlet.

35. 3. In a charge forming apparatus for internal combustion engines, a carbureter proper having a contact space provided with air and fuel inlets, a float chamber provided with a fuel inlet and a fuel outlet, and the crank case of an internal combustion engine, a member having passages forming said fuel outlet of the float chamber and said fuel inlet of the contact space, a tubular jacket coupled at one end to said member and adapted for communicating connection at its other end with the crank case of the internal combustion engine to be filled with lubricating oil from the latter, a tube extending through said jacket for conducting the fuel from the fuel outlet of the float chamber to the fuel inlet of the contact space, said tube having an intermediate portion disposed outside of and adjacent said other end of the jacket and forming a heating coil adapted to be submerged in the body 40 of lubricating oil within the engine crank case, said member having a still further passage forming a vapor inlet for the contact space, and a pipe extending through said jacket for conducting oil vapors from the crank case of the engine to said vapor inlet, said pipe having upwardly projecting branch inlets at one end adapted to extend upwardly through and above the level of the 45 oil in the engine crank case at opposite sides of said coil, said tube being extended through said pipe.

oil in the engine crank case at opposite sides 45 of said coil.

7. In a charge forming apparatus for internal combustion engines, a carbureter proper having a contact space provided with air and fuel inlets, a float chamber provided with a fuel inlet and a fuel outlet, and the crank case of an internal combustion engine, a member having passages forming said fuel outlet of the float chamber and said fuel inlet of the contact space, a tubular jacket coupled at one end to said member and adapted for communicating connection at its other end with the crank case of the internal combustion engine to be filled with lubricating oil from the latter, a tube 50 extending through said jacket for conducting the fuel from the fuel outlet of the float chamber to the fuel inlet of the contact space, said tube having an intermediate portion disposed outside of and adjacent said other end of the jacket and forming a heating coil adapted to be submerged in the body 55 of lubricating oil within the engine crank case, said member having a still further passage forming a vapor inlet for the contact space, and a pipe extending through said jacket for conducting oil vapors from the crank case of the engine to said vapor inlet, said pipe having upwardly projecting branch inlets at one end adapted to extend 60 upwardly through and above the level of the oil in the engine crank case at opposite sides of said coil, said tube being extended through said pipe.

8. In a charge forming apparatus for internal combustion engines, a carbureter proper having a contact space provided with air and fuel inlets, a float chamber provided with a fuel inlet and a fuel outlet, and the crank case of an internal combustion engine, a member having passages forming said fuel outlet of the float chamber and said fuel inlet of the contact space, a tubular jacket coupled at one end to said member and adapted for communicating connection at its other end with the crank case of the internal combustion engine to be filled with lubricating oil from the latter, and a tube extending through said jacket for conducting the fuel from the fuel outlet of the float chamber to the fuel inlet of the contact space, a rigid foraminous tube secured about and in spaced concentric relation to said member and its fuel outlet 75 passage and having a strainer screen thereon.

9. In a charge forming apparatus for internal combustion engines, a carbureter proper having a contact space provided with air and fuel inlets, a float chamber provided with a fuel inlet and a fuel outlet, and the crank case of an internal combustion engine, a member having passages forming said fuel outlet of the float chamber and said fuel inlet of the contact space, a tubular jacket coupled 80

at one end to said member and adapted for communicating connection at its other end with the crank case of the internal combustion engine to be filled with lubricating oil 5 from the latter, a tube extending through said jacket for conducting the fuel from the fuel outlet of the float chamber to the fuel inlet of the contact space, a rigid foraminous tube secured about and in spaced concentric relation to said member and its fuel outlet passage and having a strainer screen thereon, and a bowl forming said float chamber and having a partition and a depression forming a sediment trap chamber between the float 10 chamber and its fuel inlet.

10. The combination with a carbureter having a contact space provided with air and fuel inlets, a float chamber provided with a fuel inlet and a fuel outlet, and the 20 crank case of an internal combustion engine, of a tube to conduct the fuel from said fuel outlet of the float chamber to said fuel inlet of the contact space and having a portion forming a heating coil adapted to be submerged 25 in the body of lubricating oil in the crank case of the internal combustion engine, means including a pipe encasing the major portion of said tube for conducting oil vapors from the engine case to said con-

tact space, means for regulating the flow of 30 fuel into the contact space, and means for regulating the flow of oil vapors into said contact space.

11. The combination with a carbureter having a contact space provided with air and 35 fuel inlets, a float chamber provided with a fuel inlet and fuel outlet, and the crank case of an internal combustion engine, of a tube to conduct the fuel from said fuel outlet of the float chamber to said fuel inlet of the 40 contact space and having a portion forming a heating coil adapted to be submerged in the body of lubricating oil in the crank case of the internal combustion engine, means including a pipe encasing the major portion of 45 said tube for conducting oil vapors from the engine case to said contact space, means for regulating the flow of fuel into the contact space, means for regulating the flow of oil vapors into said contact space, and outlet 50 pipe for the contact space, a normally closed suction opened valve controlling the passage of the mixture from the contact space, and suction-operated mixing devices in said outlet pipe.

In testimony whereof I affix my signature.

GEORGE KUKOVAC.
